UNITED STATES PATENT OFFICE.

FRANKLIN CLAIR BREUCKMAN, OF MACKINAC ISLAND, MICHIGAN, ASSIGNOR OF
ONE-HALF TO GEORGE THOMAS ARNOLD, OF MACKINAC ISLAND, MICHIGAN.

LINE-SPACING ATTACHMENT FOR TYPE-WRITERS.

1,251,747.

Specification of Letters Patent.

Patented Jan. 1, 1918.

Original application filed July 7, 1917, Serial No. 179,170. Divided and this application filed September 24, 1917. Serial No. 193,008.

To all whom it may concern:—

Be it known that I, FRANKLIN C. BREUCKMAN, a citizen of the United States, residing at Mackinac Island, in the county of Mackinac and State of Michigan, have invented 5 certain new and useful Improvements in Line-Spacing Attachments for Type-Writers, of which the following is a specification, reference being had to the accompanying 10 drawings.

This invention relates to an improved line spacing attachment for typewriters, and has for its primary object to provide a very simple and positively operating device for automatically rotating the platen when the carriage is returned after the writing of each line, which is particularly designed for use in conjunction with typewriting machines equipped with means for automatically returning the carriage such, for instance, as that shown and described in my pending application for patent, Serial Number 179,170, filed July 7, 1917, and of which application the present invention constitutes 25 a division.

It is another important object of my invention to provide a line spacing device for typewriters which is applicable to the Underwood Standard typewriter without necessitating any structural changes whatsoever in any of the machine parts.

The invention has for one of its more particular objects to provide a line spacing device including a slidable part mounted on 35 the carriage frame and operatively connected to a part of the platen rotating mechanism, and a fixed abutment or stop with which said slidable part engages at the end of the return movement of the carriage 40 whereby the platen is rotated to properly space the lines.

It is also a further general object of the invention to provide a device for the above purpose which consists of comparatively 45 few elements of very simple form so that the device as a whole may be manufactured and applied to the typewriter at relatively small cost.

With the above and other objects in view, 50 my invention consists in the novel features of construction, combination, and arrangement of parts to be hereinafter more fully described, claimed, and illustrated in the accompanying drawings, in which,

Figure 1 is a top plan view of a type-writing machine illustrating the preferred embodiment of my improved line spacing attachment applied thereto; 55

Fig. 2 is a front elevation, the scale bar of the machine being removed; 60

Fig. 3 is an enlarged transverse section taken on the line 3—3 of Fig. 1.

Fig. 4 is a similar view taken on the line 4—4 of Fig. 1; and

Fig. 5 is a detail perspective view of the 65 slide member removed from the carriage frame.

Referring in detail to the drawings, 5 designates the carriage frame of an Underwood Standard typewriter having the usual 70 paper guide plate 6 and the platen roller 7. As the construction, mounting, and manner of operation of the carriage is well known in the art and constitutes no part of my present invention, the same will not be 75 further described in detail. It will suffice to state, for the purposes of the present explanation, that the carriage frame includes the front longitudinal bar 8 which is of angular form in cross-section. Centrally of 80 this bar, the usual outwardly projecting pointer or index member 9 is arranged for movement over the scale bar 10. 11 designates the finger bar, by means of which the platen rotating mechanism is actuated. 85

In the preferred embodiment of the present invention, I provide an arm 12 which is secured to the carriage frame bar 8 and, at the rear side and centrally thereof, by means of the screw indicated at 13. This arm extends obliquely upwardly and forwardly and its other end which is disposed immediately above the forwardly projecting enlargement on said bar is of inverted U-shaped form, as indicated at 14. This end of the arm constitutes a bearing to receive the trunnions of a roller 15. A strip of woven tape or webbing 16 extends over this roller and one end of said tape is attached to the under side of the finger bar 11 in advance of the 100 carriage frame bar by any preferred means. Upon the bar 8 on the right hand side of the arm 12 and in spaced relation thereto, a plate 18 is arranged, one edge of said plate being bent outwardly and downwardly as 105 at 19. This plate at its other edge is securely fixed to the frame bar by means of spaced screws 20 which also secure to the

frame bar a second relatively narrow metal plate 21 disposed between the edge of the plate 18 and the carriage frame. This plate 21 has its forward longitudinal edge which 5 projects over the edge of the bar 8, downwardly offset as at 22, and disposed in the same plane with the inwardly turned edge portion 19 of the plate 18. The opposite edges of the metal plates 19 and 22 are 10 spaced from each other and also from the under side of the plate 18, thereby forming a guide-way 23 to receive the flange 25 formed upon one end of a lug 24 which extends downwardly below the plate 18. Upon 15 the right hand end of the plate 18, a roller 26 is mounted in spaced bearings 27 fixed to the end edge of the plate, and over this roller the tape 16 is engaged. The end of the tape is provided with a suitable eye for 20 engagement with a headed stud 28 fixed in the flange 25 on the lug 24.

29 designates the adjustable carriage stop with which the typewriter is equipped, said stop limiting the return movement of the 25 carriage and determining the length of the written lines. To the rear portion of this adjustable stop, an upwardly projecting finger or lug 30 is suitably fixed.

From the above description, the manner 30 of operation of my invention will be readily understood. When the carriage is returned to its initial position for writing a new line, just prior to the end of such return movement, the lug 24 strikes the upwardly projecting finger 30 on the adjustable carriage stop, whereby this lug 24 is shifted in the guide-way 23 formed by the plates 18 and 21. The end of the tape 16 being attached to the lug 24, it is apparent that the tape 35 will be pulled around the roller 26 and, as the other end of the tape is connected to the spring-held, manually operable lever 11, this lever will be pulled over toward the right and the platen rotating mechanism 40 will be actuated to rotate the platen to the extent for which the mechanism has been adjusted. As the operator proceeds with the writing and the carriage again moves toward the left, the lug 24 moves away from 45 the upstanding finger 20 and the lever 11 is returned to its normal position by means of the usual lever spring, thereby also returning the lug 24 to its original position in the right hand end of the guide-way 23. 50 Thus, the platen will be properly rotated to space the written lines without necessitating any manual manipulations of the mechanism. It is further to be observed that the use of the present invention necessitates no 55 changes whatever in the construction of the platen rotating mechanism as now used in machines of the type referred to, nor requires the slightest structural alteration in the usual platen carriage construction.

60 From the foregoing description, taken in

connection with the accompanying drawings, it will be seen that I have devised a very simple, efficient, and serviceable line spacing attachment for typewriters and one which is well adapted for use in connection 70 with various devices now known in the art for automatically returning the carriage, as well as the particular carriage returning means disposed in my pending application hereinbefore referred to. It is apparent 75 that one skilled in the art may, by resorting to simple mechanical changes in the form, mounting, and arrangement of the several elements, adapt the same for use in connection with various other makes of typewrit- 80 ing machines than that herein particularly referred to.

Therefore, it is to be understood that while I have herein specifically described what, at the present time, I believe to be the 85 preferred embodiment of the invention, I nevertheless reserve the privilege of adopting all such mechanical changes as may hereafter be found to be advisable and which may fairly be considered as within the spirit 90 and scope of the appended claims.

Having thus fully described my invention, what I desire to claim and secure by Letters Patent is:

1. The combination with a typewriter carriage provided with platen rotating mechanism, means mounted entirely upon the carriage for rotating the platen and including a member connected to a part of the platen rotating mechanism, a part movable upon 100 the carriage to which said member is operatively connected, and a relatively fixed element mounted on the typewriter frame to actuate said movable part when the carriage is returned to its initial writing position 105 whereby said member is operated to rotate the platen.

2. The combination with a typewriter carriage provided with platen rotating mechanism, of a flexible element longitudinally 110 movable on the carriage and operatively connected to a part of the platen rotating mechanism, a slide member mounted on the carriage to which said flexible member is attached, and a relatively stationary lug 115 mounted on the typewriter frame with which said member is adapted to engage when the carriage is returned to its initial writing position, whereby said flexible member is moved and said part operated to rotate the 120 platen.

3. The combination with a typewriter carriage provided with platen rotating mechanism, of a member longitudinally slidable on the carriage, a flexible operative connection 125 between said member and a part of the platen rotating mechanism, and means mounted in the frame of the machine for engagement by said slide member when the carriage is returned to its initial writing po- 130

- sition, whereby said member is moved to operate said part and rotate the platen.
4. The combination with a typewriter carriage provided with platen rotating mechanism of a slide member longitudinally movable upon the carriage, a flexible operating connection between said member and a part of the platen rotating mechanism, guide means for said operating connection, and means mounted in the frame of the machine to be engaged by said slide when the carriage is returned to its initial writing position, whereby the slide is moved to operate said part and rotate the platen.
5. The combination with a typewriter carriage provided with platen rotating mechanism, of a support fixed to the carriage and having a guideway extending longitudinally of the carriage, a member slidable in said guideway, a roller mounted upon the support, a flexible element connected to said member and movable over said roller, said element being connected at its other end to said part of the platen rotating mechanism,

and means mounted in the machine frame 25 engaged by said member when the carriage is returned to its initial writing position to operate said part and rotate the platen.

6. The combination with a typewriter carriage provided with platen rotating mechanism, of a member mounted for longitudinal movement on the carriage, a flexible element connected to said member and to a part of the platen rotating mechanism, a bar fixed at one end to the carriage, a roller mounted 30 in the other end of said bar over which said flexible connection is movable, and a relatively fixed lug mounted in the machine frame with which said member is adapted to engage when the carriage is returned to its 35 initial writing position, whereby said part is operated and the platen rotated.

In testimony whereof I hereunto affix my signature in the presence of two witnesses.

FRANKLIN CLAIR BREUCKMAN.
